CHARLES S. LAWSON, OF PITTSBURGH, PENNSYLVANIA, ASSIGNOR TO WESTINGHOUSE ELECTRIC AND MANUFACTURING COMPANY, A CORPORATION OF PENNSYLVANIA.

HIGH-REACTANCE CORE-TYPE TRANSFORMER.

1,275,946.

Specification of Letters Patent. Patented Aug. 13, 1918.

Application filed April 4, 1916. Serial No. 88,806.

To all whom it may concern:

Be it known that I, CHARLES S. LAWSON, a citizen of the United States, and a resident of Pittsburgh, in the county of Allegheny and State of Pennsylvania, have invented a new and useful Improvement in High-Reactance Core-Type Transformers, of which the following is a specification.

My invention relates to electrical apparatus, and it has special relation to stationary alternating-current transformers of the core type of construction.

More particularly, my invention relates to transformers of the above indicated character in which it is desired to secure high internal reactances in order to limit, to safe values, the currents that may flow through the windings of the transformers when they are subjected to short circuits or other conditions that may occasion the flow of abnormally high currents. Transformers embodying my invention may also be used in connection with rotary converters in order to provide an external reactance drop on the alternating-current side, thereby automatically compounding the converters in a manner well-known in the art.

Core-type transformers, because of their form of construction, namely, that of having a single magnetic circuit for each group of coils, have an inherently low internal reactance. In this respect, they differ from shell-type transformers in which the several groups of coils are surrounded or inclosed by magnetizable material, thereby providing a plurality of magnetic circuits for each group of coils. Since a core-type transformer has an inherently low internal reactance it is necessary to add a magnetic-leakage path or paths between its primary and secondary windings in order to increase the internal reactance thereof to such a value as will protect the transformer from the flow of abnormally high currents when it is subjected to short circuits or other conditions which tend to increase the current-flow to an abnormally high value. Of course, it will be understood that high-reactance transformers are frequently desired in connection with rotary converters in order to automatically compound them, as mentioned above.

While the internal reactance of a core-type transformer may be substantially increased by adding magnetic leakage paths

of relatively low reluctance for the leakage flux between the primary and secondary windings it is necessary, especially in transformers adapted for high-voltage service, to thoroughly insulate the several windings from one another and also from the core member.

For the accomplishment of the above mentioned objects, my present invention is particularly designed. By means of the present invention core-type transformers are provided that have high internal reactances, and at the same time, are of a simple form of construction which permits the primary and secondary windings to be adequately insulated from each other. Moreover, transformers embodying a form of my invention are easily assembled and only slightly more cumbersome than low-internal-reactance core transformers of the usual type.

For a better understanding of the nature and scope of my invention, reference may be had to the following description and the accompanying drawing in which Figure 1 is a side view of a core-type transformer that embodies a form of my invention; Fig. 2 is an enlarged view, partially in elevation and partially in section, of a portion of the transformer of Fig. 1, showing, in detail, the structure by means of which I secure a high internal reactance, and Fig. 3 is a plan view taken along the line 1—2 of Fig. 2.

Referring to Fig. 1, which shows a core-type transformer, each leg 3 and 4 of a magnetizable core member 4^a is embraced by coils 5 which constitute the low-tension winding of the transformer and coils 6, spaced from the coils 5, which constitute the high-tension winding of the transformer. The coils 5 and 6 are insulated from the core member by means of insulating washers 7 that are placed at the top and bottom of the core legs 3 and 4 in order to space the windings from the yoke portions of the core member. Between the low-tension coils 5 and the high-tension coils 6 I place bundles of magnetizable strips 8 by means of which I establish leakage paths of low reluctance to enhance the flow of the magnetic leakage flux between the primary and secondary windings. I propose to construct these leakage paths in the manner shown in Figs. 2 and 3, to which reference may now be had.

Referring specifically to Figs. 2 and 3, the core member 4 is of the cruciform-type and the yoke portions of the core member extend beyond the core legs 3 and 4 a sufficient distance, as shown, to substantially bridge the space between the low-tension or secondary coils 5 and the high-tension or primary coils 6. Each side of the cruciform-core leg 3 is provided with insulating covering 9 of channel shape which extends beyond the corners of the core leg in order to thoroughly insulate therefrom the immediately adjacent low-tension coil 5 which is wound in circular form in the usual manner. The low-tension winding, in this instance, comprises a plurality of coils 5 and 5^a which are spaced from each other by means of wooden spacing strips 10 that are placed at intervals between these coils so as to provide a series of ventilating ducts 11 through which the insulating oil may freely flow. On two opposite sides of the core leg 3, I place a plurality of groups or bundles 8 of magnetizable strips which are intermediate the low-tension coils 5 and 5^a and the high-tension coils 6 and 6^a. The several groups 8 of magnetizable strips are interposed between the low-tension and the high-tension coils only at the places subtended by the yoke portions of the core member 1. The strips 8, therefore, form low-reluctance paths for the flow of the magnetic leakage flux, inasmuch as they are auxiliary, or placed in shunt, to the core leg 3 which is traversed by the main portions of the transformer flux. Each bundle 8 of laminations is bolted, at its top and bottom, to a segment 12 of insulating material, preferably micarta, and to an insulating cylinder 13 which likewise may be made of micarta. Bolts 14 extend through each bundle 8 of laminations and through the walls of the insulating barriers 12 and 13 in order to firmly hold the laminations in place and to permit the whole to be bodily lifted, when desired. As many bundles 8 are employed as are necessary to provide the required internal reactance and they are secured to the insulating cylinder 13 before assembling the transformer. The ends of the insulating segments 12 are bolted to wooden or insulating blocks 14^a, which, in turn, are secured to the insulating cylinder 13. In this manner, the spaces intermediate the insulating segments 12 and the cylinder 13 that are occupied by the bundles 8 of laminations are closed, except for the vertical ventilating ducts intermediate adjacent bundles 8. Other wooden blocks 15 retain the insulating cylinder 13 and its associated structure in a fixed position relative to the low-tension coils 5 and 5^a. External to the insulating cylinder 13 are placed other wooden or insulating blocks 16 which space the high-tension coils 6 from the insulating cylinder 13. An-

other group of insulating blocks 17 are interposed between the high-tension coils 6 and 6^a in order to provide a plurality of vertical ventilating ducts therebetween.

From the foregoing description, it will be noted that auxiliary magnetic paths of relatively low reluctance are inserted below the low-tension coils 5 and 5^a and the high-tension coils 6 and 6^a in order to increase the amount of leakage flux that may flow between the primary and secondary windings which, as is well-known, increases the internal reactance of the transformer. The bundles 8 are so placed relative to the yoke portions and the core legs 3 and 4 of the transformer core that they provide paths for the magnetic flux which are auxiliary to the main paths furnished by the core legs 3 and 4. In order to regulate or adjust the quantity of the leakage flux traversing each auxiliary path, the bundles 8 may comprise a plurality of superposed groups 8^a and 8^b, as shown in Fig. 2, which are spaced from one another by means of insulating strips 18. The interpositioning of the insulating strips 18 is equivalent to providing air gaps in the magnetic circuit. By adjusting the number of strips 18, the length of the air gaps may be regulated so as to vary, at will, the reluctance of the auxiliary paths provided by the bundles 8.

From the foregoing description, it will be apparent that the high-tension and low-tension coils are adequately insulated from one another, and, at the same time, have leakage paths established therebetween by means of which any desired amount of leakage may be directed from the main magnetic path. The bundles 8 are firmly secured in place and, by reason of their being attached to the insulating barriers 12 and 13, may be readily applied when assembling the transformer.

While I have shown and described one embodiment of my invention, it will be understood that many modifications may be made without departing from the spirit and scope of the appended claims.

I claim as my invention:

1. A transformer comprising a core member, primary and secondary concentrically disposed and spaced coils embracing the same core leg of said member, a cylindrical insulating barrier separating said coils from each other throughout their entire length and severally providing ventilating passageways between them, and magnetizable shunts secured to said barrier and placed to increase the leakage flux between said coils.

2. A transformer comprising a core member, concentrically disposed and spaced primary and secondary coils embracing a core leg thereof, an insulating barrier interposed between said coils, and a plurality of mag-

netizable shunts secured to said barrier and disposed in parallel relationship to the core legs.

3. A transformer comprising a rectangular core member having core legs and yoke portions, primary and secondary nested coils embracing the core legs, and a plurality of magnetizable shunts interposed between said nested coils which bridge the spaces subtended by the yoke portions only of the core.

4. A core type transformer comprising a rectangular core member having core legs and yoke portions, primary and secondary coils embracing the core legs thereof, insulating barriers interposed between the primary and secondary coils, and magnetizable shunts secured to the insulating barriers and bridging the spaces subtended by the yoke portions only.

5. A core-type transformer comprising a

core member having core legs and yoke portions, primary and secondary coils embracing the core legs thereof, cylindrical insulating barriers interposed between the primary and secondary coils having magnetizable shunts attached to opposite sides thereof and bridging the spaces subtended by the yoke portions only.

6. A core-type transformer comprising a core member having core legs and yoke portions, the yoke portions extending laterally beyond the core legs, primary and secondary coils embracing the core legs, and magnetizable shunts extending between the laterally projecting yoke portions to increase the leakage flux between the primary and secondary coils.

In testimony whereof I have hereunto subscribed my name this 31st day of March, 1916.

CHARLES S. LAWSON.
